CLAIM

The ornamental design for a transmitting and receiving apparatus for data communication, as shown and described.

DESCRIPTION

FIG. 1 is a front view of a transmitting and receiving apparatus for data communication showing our new design;

FIG. 2 is a rear view thereof;

FIG. 3 is a left side view thereof;

FIG. 4 is a right side view thereof;

FIG. 5 is a top side view thereof;

FIG. 6 is a bottom side view thereof; and,

FIG. 7 is a perspective view of the transmitting and receiving apparatuses for data communication of our new design attached to an antenna and a pole and connected to a data communication apparatus.

The broken lines in FIG. 7 depict environmental subject matter only and forms no part of the claimed design.

The broken lines in FIGS. 2-6 depict parts of the transmitting and receiving apparatus for data communication that form no part of the claimed design.
